US0D1039331S

(12) **United States Design Patent** (10) **Patent No.:** **US D1,039,331 S**
(45) **Date of Patent:** **** Aug. 20, 2024**

(54) **VACUUM BOTTLE**

(71) Applicant: **Shenzhen Crastal Technology CO. LTD**, Shenzhen (CN)

(72) Inventors: **George Mohan Zhang**, Shenzhen (CA); **Yanxin Lu**, Shenzhen (CN); **Zhen Sun**, Shenzhen (CN)

(73) Assignee: **SHENZHEN CRASTAL TECHNOLOGY CO. LTD**, Guangdong (CN)

(**) Term: **15 Years**

(21) Appl. No.: **29/835,085**

(22) Filed: **Apr. 15, 2022**

(30) **Foreign Application Priority Data**

Apr. 7, 2022 (CN) 202230190478.0

(51) **LOC (14) Cl.** **07-01**

(52) **U.S. Cl.**

USPC **D7/511**; D7/510

(57) **CLAIM**

The ornamental design for a vacuum bottle, as shown and described.

DESCRIPTION

FIG. 1 is a front and top perspective view of a vacuum bottle, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the vacuum bottle that form no part of the claimed design.

1 Claim, 8 Drawing Sheets
